H. C. BASCOM.
COOKING STOVE.

No. 15,678.

Patented Jan. 6, 1885.

UNITED STATES PATENT OFFICE.

H. CLAY BASCOM, OF TROY, NEW YORK.

DESIGN FOR A COOKING-STOVE.

SPECIFICATION forming part of Design No. 15,678, dated January 6, 1885.

Application filed October 20, 1884. Term of patent 7 years.

To all whom it may concern:

Be it known that I, H. CLAY BASCOM, a citizen of the United States, residing in the city of Troy, in the county of Rensselaer and State of New York, have invented and produced a new and original Design for a Cooking-Stove, of which the following is a specification, reference being had to the accompanying engraving of a cooking-stove having said design.

10 This design relates to new and distinctive parts and combinations of parts which go to make up the whole design, as hereinafter specified.

One complete distinctive part of this design 15 is the ornamentation of the door B, having the form shown, which ornamentation consists of the compound ornamented arch e, the two standing ornaments f at the ends of the arch, the compound lower corner ornaments, 20 g, the ornamented beadings h, connecting the two ornaments g, and the two standing beadings i, connecting the ornaments g with the ends of the arch e, as shown. A further part of this design is the shape and ornamentation 25 of the oven-door, of the form shown, and embracing the ornamental border e f g h i, as above specified, in combination with the raised plate ornament A, having the form of an ellipse, with the four acute-angled projections a, that appear to be parts of two triangular figures which extend to the center of the plate, and have therein the spreading in-cut ornaments b, and are crossed by the end bars of the rectangular figures c, while the in-cut ornaments d are in the outer side portions 30 of the plate-face. Another part relates to the ornamentation of the rectangular door C, consisting of the compound scroll form and floret central ornament, j, and the compound top 35 and bottom ornamental arches, k, with the corner ornaments, l. The ornamentation of the quadrilateral panels D and E consists of the central panel ornament, m, the ornamental arch n, with the end ornaments, n', the compound lower corner ornaments, o, with the bottom connection, o', and the lateral connections o². The ornamentation of the common-shaped side plate, F, consists of the compound scroll and floral ornament p on the forward 45 extension, q, having the curved front end mold-

ing, q', and the molding q² along the bottom and rear borders of the plate.

The design for the front of the stove embraces the upper front plate, having the overhanging convexly-curved upper part; the door 55 G, consisting of the flat upper part, r, having the three quadrilateral mica lights r', with curved truncate corners; the inclined nameband s, and the flat lower part, t, having the four oblong apertures t', with the lower corners rectangular, and the upper ones truncate; the hearth, extending upward and rearward along the sides of the stove, and the concavely-curved lower front plate, as shown.

The design for the stove-support embraces 65 the side skirting, H, having the central ornament, u, lateral ornaments u', and ornamental border parts v v', the end skirting, I, having the central ornament, w, lateral ornaments w', and the ornamental border parts x x', and the 70 legs having the ornaments y.

The design for the legs J embraces the central compound ornament, y, on the surface y', which is curved convexly in the middle, and has its lateral portions curved at their ends 75 and in planes at right angles to each other, and the convexly-curved and downwardly-contracted lower portion, z.

The whole design embraces the shape and ornamentation of the top, the side, including 80 the panel-plate A, doors B C, panels D E, and plate F, the front, including the hearth and door G, the bottom, the skirtings H I, and the legs, substantially as shown in the accompanying engraving.

I claim as new—

1. In a design for a stove, the ornamentation of the door B, consisting of the ornamental parts e f g h i, as shown and described.

2. In a design for a stove, the shape and ornamentation of the oven-door of the form shown, and having the border ornaments e f g h i, and the plate ornament A, having the parts a b c d, as set forth.

3. In a design for a stove, the ornamentation 95 of the rectangular door C, embracing the parts j k l, as shown and described.

4. In a design for a stove, the ornamentation of the quadrilateral panels D E, consisting of the parts m n n' o o' o², as shown and described. 100

5. In a design for a stove, the shape and ornamentation of the side plate, F, embracing the parts p , q , q' , and q'' , as shown and described.
- 5 6. In a design for a stove, the shape and ornamentation of the front, embracing the over-hanging convexly-curved upper part, the door G, having the ornamental parts r r' s t t' , as specified, the hearth having upward and rear-
10 ward side extensions, and the retreating concavely-curved lower front plate, as shown and described.
- 15 7. In a design for a stove, the stove-support embracing the side skirting, H, having the ornamental parts u u' v v' , the end skirting, I, having the ornamental parts w w' x x' , and the legs having the ornament y , as set forth.
8. In a design for a stove, the shape and ornamentation of the legs J, embracing the parts y y' z , substantially as shown and described. 20
9. The design for a cooking-stove, embracing the top, the side, including the parts A B C D E F, the front, including the hearth and door G, the bottom, the skirtings H I, and the 25 legs, shaped and ornamented substantially as set forth.

In testimony whereof I hereunto set my hand,
in the presence of two subscribing witnesses,
this 17th day of October, 1884.

30

H. CLAY BASCOM.
